SCREENING MACHINE

Alfred L. Adrianson, Racine, Wis.

Application November 15, 1939, Serial No. 304,515

5 Claims. (Cl. 209—326)

This invention relates to screening machines, and more particularly to such a machine which is durable, efficient, adaptable to a wide variety of uses and has a large capacity for its size and weight.

Although the screening machine disclosed herein may be made in sizes to suit particular applications and purposes, the structure is such that a relatively small and portable machine is suited to the screening or sifting of substances such as dry sand, damp moulding sand, compost, chemicals and pigments. Also, in addition to having large capacity as compared to the size and weight of the machine, the structure is such that the screens are easily and quickly changeable for varying the uses, and during use the screen is secured in such a way that the life thereof is prolonged.

It is an object of this invention to provide a screening machine having relatively large screening capacity compared to size and weight of the machine.

Another object of this invention is to provide a screening machine in which the screens are easily interchangeable and the screen being used is held in such a way that whipping and breaking of the screen are minimized.

Another object of this invention is to provide a screening machine having an unobstructed screen surface through which materials are sifted and elements cooperating with the screen for increasing the speed of screening and the capacity of the machine.

Another object of this invention is to provide a screening machine which is unitary in structure and readily movable.

Other objects and advantages of this invention will be apparent from the following description of the structure and operation of the disclosed embodiment thereof having reference to the accompanying drawings wherein one form of screening machine which embodies the invention is clearly shown.

In the drawings:

Figs. 1, 2 and 3 are respectively side, top and end elevations of a screening machine embodying a preferred form of this invention;

Figs. 4, 5 and 6 are fragmentary sectional views of portions of the device shown in Figs. 1, 2 and 3, with the sections taken substantially on lines 4—4, 5—5 and 6—6 of Fig. 2, respectively, and viewed in the directions indicated by the arrows, and

Fig. 7 is a side elevation of a preferred form of one part of the screening machine, showing

the preferred normal disassembled form thereof.

Having particular reference to the drawings, a screen frame 8, having sides 9 and 10 and ends 11 and 12, serves as a receptacle for the material which is to be sifted by the screening machine. The sides 9 and 10 are secured to angularly disposed portions 11a and 12a of the ends 11 and 12 by rivets or other suitable fastening means, such as 13. Brackets 15 and 16 are secured to the sides 9 and 10 respectively by screws such as 17, or other suitable fastening means. Curved or semi-elliptical leaf springs 18 and 19 are secured at their mid-portion to the brackets 15 and 16 respectively by bolts or other suitable fastening means such as 20 and 21. The ends of the leaf springs 18 and 19 are secured to and supported by a base 22 comprising a pair of substantially U-shaped supports 23 and 24 which are secured together at their outer ends by a pair of substantially rigid braces 25 and 26; the springs 18 and 19 being secured at their ends to angularly disposed portions 27 and 28 of the U-shaped support 23 and angularly disposed portions 29 and 30 of the substantially U-shaped support 24 by bolts such as 31 and 32. The braces 25 and 26 are respectively secured to the substantially U-shaped supports 23 and 24 by bolts 33 and 34 or other suitable fastening means. By this construction the screen frame 8 is resiliently supported from the base 22 through the leaf springs 18 and 19.

In the preferred embodiment of this invention, a motor or prime mover 35 is secured directly to the end 12 of the screen frame 8 near the mid-portion of that end. The motor or prime mover 35 has a shaft 36 which extends outwardly at each end of the motor and has eccentric or unbalanced weights or fly wheels 37 and 38 secured to the extending ends of the shaft. The fly wheels or weights 37 and 38 are preferably unbalanced by being cut away as at 39 and 40 and the cut-away portions are preferably aligned so that the eccentric weights are in phase. Also the motor or prime mover 35 is preferably so positioned that the axis of the shaft 36 is substantially perpendicular to the longitudinal planes of the leaf springs 18 and 19. A broad shield 42 is provided for the motor 35, which also serves to clamp the motor onto the screen frame, and eccentric weights or fly wheels 37 and 38 by a plate having its edges secured to the end 12 of the screen frame 8 by rivets 43 and 44 or other suitable fastening means and bowed outwardly around the motor and fly wheels. This combination clamp 55 and shield 42 assists in holding the motor 35 se-

surely in position and also protects the motor and fly wheels from material being put into the screening machine.

To effect proper balance between the screen frame 8 and the attached motor 35 for stable support through the springs 18 and 19 and to obtain improved vibratory movement of the screen frame 8 as a result of the rotation of the eccentric fly wheels or weights by the motor 35, the brackets 15 and 16 are preferably disposed nearer to the end 12 which supports the motor than to the end 11 of the screen frame.

For accomplishing the screening or sifting of material put into the screen frame 8, a screen 46 extends across the screen frame from end to end and from side to side. This screen 46 may be of any desired mesh and is preferably secured to the screen frame 8 so as to be interchangeable with other screens and so that the upper surface thereof is practically unobstructed. As illustrated in Fig. 4, the screen 46 is looped over angularly disposed portions 47 of strips 48 at each end. Clamping and stretching members 49 and 50 having angularly disposed portions such as 51 extend across each end of the screen frame 8 and engage and secure the screen as at 52. These clamping and stretching members 49 and 50 when drawn toward the ends 11 and 12 respectively by bolts such as 53 having cooperating wing nuts 54 secure the ends of the screen and stretch it tautly between the ends of the screen frame 8.

Angle irons 46^a are secured by rivets b or the like to the screen frame around the bottom thereof so that the marginal portions of the screen 46 rest thereon and to prevent whipping and consequent breaking of the screens during operation of the screening machine, normally bowed strips such as 55 and 56, one of which is illustrated in its normal form in Fig. 7, are secured in position against the sides of the upper surface of the screen by curved and somewhat resilient clamping arms or fingers 58, 59, 60 and 61. The clamping fingers or arms 58 and 60 are secured to the clamping member 49 by rivets such as 62 or other suitable means. The clamping fingers or arms 59 and 61 are secured to the clamping member 50 by rivets such as 63, or other suitable means. The downward pressure of the flattened out bowed strips 55 and 56 holds the marginal portions of the screen 46 firmly against the supporting angle irons 46^a.

The sides 9 and 10 of the screen frame 8 preferably extend downwardly below the surface of the screen 46 as illustrated in Fig. 6. Resilient arms 65, 66 and 67 each have an angularly disposed end such as 68 in Fig. 6 secured to the side 10 below the surface of the screen 46 by bolts 69 having cooperating nuts 70 or other suitable fastening means. These resilient arms extend inwardly with respect to the side 10 along and substantially parallel to the lower surface of the screen 46 and in normal spaced relation thereto. The arms 65, 66 and 67 are preferably of different lengths and pads or tappers 71, 72 and 73, respectively, are secured to the extending ends thereof by rivets such as 74. The pads or tappers 71, 72 and 73 are preferably made of rubber or some similar material which is resilient and relatively soft. Resilient arms 75, 76 and 77 are preferably substantially oppositely disposed with respect to the arms 65, 66 and 67 and are similarly secured to the side 9 of the screen frame. The arms 75, 76 and 77 have tappers 78, 79 and 80 respectively secured thereto by rivets, bolts or other appropriate means as shown at 81. The arms 75, 76 and 77

are also preferably of different lengths and it is preferable that the lengths of the oppositely disposed arms 65 and 75 and 67 and 77 are different.

The operation of the motor 35 is controlled by a switch 83 which is mounted on a bracket 84. The bracket 84 is secured to and supported by the bracket 16 or by any other convenient part of the apparatus.

In the operation of the screening machine herein disclosed, a screen of the proper or desired mesh is first secured to the ends of the screen frame as previously described, while the resilient strips 55 and 56 are removed. After the screen is tautly stretched between the ends, the resilient strips 55 and 56 are inserted between the screen 46 and the clamping arms 58, 59, 60 and 61. It will be understood of course that the ends of the strips 55 and 56 curve upwardly before they are secured in position beneath the clamping arms 58, 59, 60 and 61. In changing screens, the resilient strips 55 and 56 are removed and then the screen is released from the clamps at the end of the screen frame.

Rotation of the eccentric or unbalanced weights or flywheels by the motor 35 causes a vigorous vibration of the screen frame and screen so that material put into the screen frame is rapidly sifted by the screen. The resilience of the resilient arms 65, 66, 67, 75, 76 and 77 and the mass of the pads or tappers 71, 72, 73, 78, 79 and 80 are so proportioned that the vibration of the screen frame 8 effects the vibration of the resilient arms at a period such that the pads or tappers continually tap the surface of the screen. The tapping of the screen surface by these pads or tappers increases the speed and efficiency of the machine and also helps to keep the screen openings clean. Since both surfaces of the screen are relatively unobstructed, the effective screening area of the screen is maximum.

While the embodiment of the present invention which is herein disclosed constitutes a preferred form, it is understood that other forms may be adopted, all coming within the scope of the claims which follow.

I claim:

1. In a screening device of the class described, the combination of a screen frame having an end wall and a pair of laterally spaced side walls with a screen interposed therebetween, said screen frame being resiliently and non-pivotaly mounted at its opposite sides at one point only on each side between its ends on long, relatively flat, semi-elliptical spring supports permitting endwise and up and down and teetering movement of the screen frame, said points of mounting being substantially within a transverse vertical plane passing through the center of gravity of the screen frame, and a rotary vibrator mounted on the end of the screen frame beyond its aforesaid end wall.

2. In a screening device of the class described, the combination of a screen frame having an end wall and a pair of laterally spaced side walls with a screen interposed therebetween, said screen frame being interposed between and mounted solely on a pair of laterally spaced springs which are non-pivotaly attached respectively to the side walls of the screen frame at one point only on each side wall between the ends thereof, said points of mounting being substantially within a transverse vertical plane passing through the center of gravity of the screen frame, and a rotary vibrator mounted on the end of the screen frame beyond its aforesaid end wall.

3. In a screening device of the class described,

the combination of a support, a screen frame having an end wall and a pair of laterally spaced side walls with a screen interposed therebetween, said screen frame being interposed between and supported solely upon a pair of laterally spaced elongated leaf springs which are non-pivottally attached substantially midway between their ends to the opposite sides of the screen frame at points substantially within a transverse vertical plane passing through the center of gravity of the screen frame, each spring being provided at each end with a core formation by which it is mounted on the aforesaid support, and a rotary vibrator mounted on the end of the screen frame beyond its aforesaid end wall.

4. In a screening device of the class described, the combination of a base member, a screen frame and vibrator unit wherein the screen frame has an end wall and a pair of laterally spaced side walls with a screen interposed therebetween and the vibrator is mounted on the end of the screen frame beyond said end wall, and long, relatively

flat, semi-elliptical springs interconnecting the base member and the screen frame and vibrator unit resiliently in longitudinally tiltable relation, one spring only on each side of the unit, the unit being non-pivottally supported on the springs substantially in a transverse vertical plane passing through the center of the unit.

5. In a screening device of the class described, the combination of a base member, a screen frame having an end wall and a pair of laterally spaced side walls with a screen interposed therebetween and a rotary vibrator mounted on the end of the screen frame beyond the said end wall, said screen frame being resiliently and non-pivottally supported between its ends solely on springs at points substantially within a vertical transverse plane passing through the center of gravity of the screen frame with its vibrator whereby to permit substantial movement of the screen frame in all directions except transversely.

ALFRED L. ADRIANSON.
